UNITED STATES PATENT OFFICE.

JOHN A. PLINT, OF BUTTE, MONTANA.

DESIGN FOR A CAN-OPENER.

SPECIFICATION forming part of Design No. 31,859, dated November 21, 1899.

Application filed October 27, 1899. Serial No. 734,992. Term of patent 14 years.

To all whom it may concern:

Be it known that I, JOHN A. PLINT, of Butte, in the county of Silver Bow and State of Montana, have invented and produced a new and original Design for a Can-Opener, of which the following is a full, clear, and exact specification.

Reference is to be had to the accompanying drawings, forming a part of this specification, in which similar characters of reference indicate corresponding parts in all the views.

Figure 1 is a perspective view of a can-opener, showing my design. Fig. 2 is a side elevation of the same, and Fig. 3 is an inverted plan view of the same.

The design in its entirety consists of a handle A, terminating at its forward end in a depending shank B, having a V-shaped back

B', forming with the sides of the shank vertically-disposed sharp edges B², and from the shank extends approximately at right angles and in a forward direction a blade C, slightly curved downwardly and of an elliptical shape.

The leading feature of the design consists of the handle having a depending shank and a forwardly and downwardly curved blade extending from the shank.

Having thus fully described my invention, I claim as new and desire to secure by Letters Patent—

The design for a can-opener herein shown and described.

JOHN A. PLINT.
